Store Fixture Company, Inc., Odenton, Md., a corpora-
tion of Maryland

Filed Nov. 3, 1960, Ser. No. 67,026

5 Claims. (Cl. 5—63)

This invention relates generally to bed frames which are constructed to permit the raising and lowering of a mattress carrying frame, and are especially adapted for use for hospital beds where it is necessary to vertically adjust the mattress carrying frame to accommodate the particular requirements of a patient.

Vertically adjustable bed frames per se have been previously proposed and some of the difficulties in vertically adjustable bed frames have been that the manual effort required to adjust the bed frames is considerable, repair and maintenance is generally difficult, chain drives and the like are utilized externally to transmit force, and when counterbalance springs are utilized, they must be carefully matched and no provision has been provided for a pre-loading of any counterbalancing means to counterbalance the weight of the frame, mattress and patient during the entire range of upward movement.

A primary object of the present invention is to provide an improved vertically adjustable bed frame which includes a novel end construction.

A further object of the invention is to provide a vertically adjustable bed frame which is counterbalanced throughout its range of vertical adjustment and in which the counterbalancing means may be adjusted and coordinated to distribute the counterbalancing force substantially across the entire structure being vertically adjusted.

Still another object of the invention is to provide an improved vertically adjustable bed frame for supporting a mattress thereon, the bed frame including a structure in which all of the operating mechanisms are enclosed, and further including means whereby mismatched counterbalancing springs may be readily coordinated to impose equally distributed forces on the entire structure being vertically adjusted.

A still further object of the invention is to provide a bed frame of the character set forth in which both end assemblies of the bed frame are counterbalanced.

And yet another object of the invention is to provide, in a bed frame of the character set forth, means whereby both ends of the bed frame are raised and lowered simultaneously.

Other objects and the nature and advantages of the instant application will be apparent from the following description taken in conjunction with the accompanying drawings wherein:

FIG. 1 is a side elevation of a novel bed frame, showing by means of phantom lines the vertically adjusted position of the mattress supporting frame and mattress;

FIG. 2 is an end view looking from right to left of FIG. 1;

FIG. 3 is an end view looking from left to right at FIG. 1;

FIG. 4 is an enlarged vertical section taken substantially on line 4—4 of FIG. 1, with portions broken away and shown in section for purposes of clarity;

FIG. 5 is an enlarged vertical section taken substantially on line 5—5 of FIG. 2;

FIG. 6 is an enlarged section taken substantially on line 6—6 of FIG. 2, with portions broken away and showing details of the operating handle of the bed frame;

FIG. 7 is a fragmentary section taken on line 7—7 of FIG. 4, showing details of the adjustable force applying means for the counterbalance means of the novel bed frame;

2

FIG. 8 is a fragmentary section taken on line 8—8 of FIG. 4, showing the manner in which the cross head for the support legs is fixed to the support legs of the frame; and

5 FIG. 9 is an enlarged vertical section taken on line 9—9 of FIG. 3.

Referring to the drawings in detail, a vertically adjustable bed frame is indicated generally at 10 and includes an end assembly 12, identified as the foot of the bed frame, an end assembly 14 identified as the head of the bed. Each of the end assemblies 12 and 14 include conventional mounting brackets 16 and 18, respectively, upon which are mounted opposite ends of conventional mattress supporting side rails 20, only one being shown. 15 Removably supported on the side rails 20 is a box spring 22 and mattress 24.

The end assembly 12 or foot of the bed includes, adjacent the upper end portion thereof, a manually operated handle assembly 26 which will be disposed substantially at the height of a person operating the bed to accordingly require a minimum of bending down when operating the mechanism.

Each of the end assemblies 12 and 14 are substantially identical, and accordingly, only the end assembly 12, i.e., 25 the foot, will be described in detail. However, it will become readily apparent to those skilled in the art that the operating handle assembly 26 may be readily incorporated on the end assembly 14, i.e. the head of the bed.

Referring to FIGS. 7 and 8, it will be noted that the 30 entire operating mechanism of the end assemblies will be enclosed by means of suitable side panels 28 and 30 constructed of any suitable material, for example, a synthetic plastic material or the like and the edges of the bed will be covered with a suitable molding strip 32. For 35 purposes of clarity and illustration, the edge molding and side panels have been removed in FIG. 4.

Referring to FIG. 4, the end assembly 12, as well as the end assembly 14, comprises a pair of vertically extending parallel support legs 34 and 36 which have a substantially rectangular cross section as seen in FIG. 8. The legs 34 and 36 each includes in the lower end portion thereof a transverse block element 38 closing the lower end and including a vertically extending internally threaded bore 40 which receives therein a threaded 40 mounting shaft 42 of a caster wheel assembly indicated 45 generally at 44.

The legs 34 and 36 include on the opposed inner surface portions thereof a horizontally disposed head member indicated generally at 46. The head member 46 50 comprises a pair of spaced rectangular plates 48 and 50, which are retained in spaced relationship by means of mounting blocks 52 and transverse nut-and-bolt assemblies 54. The blocks 52 include a longitudinally 55 projecting mounting rib 56 which extends the entire width thereof, and abuttingly engages the opposed inner surfaces of the respective legs. The mounting blocks 52 include longitudinally extending bore portions 58, see FIGS. 4 and 8, in which are received suitable fastening 60 screws 60 engaging in suitably tapped apertures in the support legs.

Fixedly secured by means of suitable nut-and-bolt assemblies 62 is a block element 64 including a vertically extending internally threaded bore 66 which will receive 65 a force transmitting adjusting screw subsequently to be described in detail.

The end assemblies 12 and 14 each includes a vertically adjustable head assembly indicated generally at 68 and upon which is mounted a force transmitting assembly indicated generally at 70. The head assembly 68 includes end sleeves 72 and 74 which are telescopically and reciprocably received on the support legs 34 and 36,

respectively, and which include a vertically extending slot portion 76, only one being shown, through which the rib portion 56 of the mounting blocks 52 extend, see FIGS. 4 and 8. Secured in horizontally extending relationship to the upper ends of the sleeves 72 and 74 is an upper head element 78 having depending therefrom a gear supporting casing 80, see FIGS. 4, 6 and 9. As seen in FIG. 6, the casing 80 has mounted on opposite side walls thereof bearings 82 and 84 in which are received an operating shaft 86 which projects from the outer surface of the end assembly 12 and is connected by means of a suitable pin 88 to an operating handle 90 of the handle assembly 26. The mounting shaft 86 has pinned thereon a drive bevel gear 92 which meshes with and drivingly engages a driven bevel gear 94. Mounted in the lower end of the casing 80 is a mounting block 96 in which is supported a roller bearing assembly 98 through which extends a reduced diameter and uninterrupted portion 100 of an adjusting or driving screw 102. The gear 94 is suitably secured at 103 to the upper end of portion 100 of the screw 102. The screw 102 threadedly engages the threaded bore 66 of the block 64 and is of a relatively shallow pitch to accordingly prevent "back-driving" by the counter-balancing means of the bed frame which will subsequently be described in detail.

Extending horizontally between lower intermediate portions of the sleeves 72 and 74 adjacent the lower end of the slots 76 is a transverse support member 104 which includes a depending casing 106 which is in substantial alignment with the casing 80. Secured in an intermediate portion of the casing 106 is a mounting block 108 in which is mounted a bearing assembly 110 and which receives a lower uninterrupted and reduced diameter portion 112 of the screw 102. Fixed to the lower end of the portion 112 of the screw 102 by means of a pin 114 is a bevel gear 116 which drivingly engages a gear 118 of a torque transmitting shaft 120, see FIGS. 4 and 5.

The casings 106 each have mounted on opposite sides thereof co-axial bearings 122 and 124. The bearings 122 and 124 on the foot end of the bed frame support the torque transmitting shaft 120 and the bearings at the head end of the bed frame support the shaft 120'. The shaft 120' includes a diametrical torque transmitting pin 125 which is received in a transverse slot 126 opening into the end of a sleeve 127 telescoped on the shaft 120'. The sleeve 127 has telescoped over its inner end one end of a sleeve 128, which is fixed to the sleeve 127 by a transverse pin 129.

The shaft 120 includes a transverse abutment pin 130 adjacent the bearing 124; see right hand side of FIG. 5, and receives on an integral torque-transmitting pin 131 the slotted end 132 of a sleeve 133 telescoped over the shaft 120. The sleeve 128 is telescoped over the inner end of sleeve 133 and includes a diametrically disposed pin 134 which is received in slot 132 of sleeve 133. A compression spring 135 extends longitudinally in the sleeve 128 and engages at one end an intermediate abutment pin 136, the other end of the spring engaging the end 137 of the sleeve 133.

The spring 135 normally urges the sleeves 128 and 127 into engagement with pin 125, and the sleeve 133 into engagement with pin 130. In order to disassemble the torque transmitting structure, the sleeves 127, 128 are moved as a unit to the right, off the end of shaft 120', and the pin 134 will move in slotted end 132 to permit separation of the sleeve 127 from the shaft 120'.

In order to protect a support surface from oil drippings and to protect the operating mechanism of the torque transmitting structure from dust and the like, the members 104 of the respective end assemblies 12 and 14 may have suitably and removably secured thereto, by means of screws 142, a housing 144 beneath each casing 106 which is readily removable for purposes of main-

tenance and prevents oil dripping and dust contamination of the gears.

In the absence of additional structure, it will be observed that by manipulating the handle 90 and rotating the shaft 86, the adjusting screws 102 in each of the respective end assemblies 12 and 14 will be rotated and react against the blocks 64 in the respective head assemblies and accordingly the sleeves 72 and 74, i.e. the head assemblies 68, will be vertically adjusted with respect to the head members 46 or the surface upon which the legs 34 and 36 are supported by the caster wheels 44.

Each of the legs 34 and 36 have extending longitudinally therein energy storing or counterbalance means comprising elongated coil springs 146, the lower ends of which engage the block 38 in the bottom of the legs. The upper ends of the springs 146 receive therein the end portion 148 of an abutment collar 150 which includes an upwardly extending, reduced diameter shaft 152. Rotatably received on the shaft 152 is an externally threaded, tubular force applying element 154, the upper end of which is received in an internally threaded abutment block 156, see FIGS. 4 and 7. The blocks 156 are secured in the sleeves 72 and 74 by means of suitable screws 158, and the block 156 includes a laterally adjustable lock screw 160 engageable with the outer surface of the force applying element 154. The upper end portion of the force applying tube 154 includes a diametrical slot 162 for receiving a suitable driving tool whereby the element 154 may be rotated through a suitable opening 164 in the molding 32, see FIG. 4.

Inasmuch as the novel bed frame is utilized particularly in hospitals, the opening 164 and open upper end of the tubular force applying element 154 will provide means whereby various rods for supporting plasma administering apparatus and the like may be readily supported.

It will be noted in FIG. 9, that the portion 100 of the adjusting screw 102 has mounted in the place of the driven gear 94, a block element 94' inasmuch as the operating handle assembly 26 is associated with the end assembly 12. If desired, the structure of the end assemblies 12 and 14 could be identical in this respect, or if preferred, the operating handle could be installed on the head of the bed instead of the foot.

As previously mentioned, the threaded portion of the adjusting or force transmitting screw of the force transmitting means 70 is of a relatively shallow pitch and the pressure applying elements 154 may be adjusted to provide the dual function of matching the counterbalancing force of the energy storing coil springs 146 as well as for the purpose of providing sufficient counterbalancing force which will not cause "back driving" of the head assemblies with respect to the support means comprising the legs 34 and 36 and the cross head 46.

Thus, when patients of different weights utilize the vertically adjustable bed of the subject invention, they may vary anywhere from 100 to 250 lbs., it is readily apparent that the counterbalancing means may be readily adjusted in a hospital without the aid of a specialized maintenance man, factory representative, etc. Further, all of the bearings utilized are self-lubricating, and accordingly maintenance in this respect is kept to a minimum. Still further, the side panels 28 and 30 of the end assemblies may be readily removed upon removal of the moldings 32 by means of removing screws 166, see FIGS. 1-3, to facilitate access to the operating mechanism of the vertically adjustable bed. Further, the panels 28 and 30, if they become damaged or a change of color is desired, may be readily replaced by new panels by means of the just mentioned expedient.

Additionally, the counterbalancing or energy storing means 146 are disposed at the outer extremities of the head assembly 68 and thus force will be applied uniformly across the head assembly, the element 78 thereof in effect acting as a simple beam. And still further, the

head assembly 46 extends a substantial length of the legs 34 and 36 and provides an exceptionally rigid structure insuring stable reaction of the adjusting screws 102 against the blocks 64. In addition, there is afforded a direct drive which eliminates the necessity for utilizing drive chains and the like which can become relatively noisy after continued use and which require frequent maintenance in order to keep the bed in proper operating condition.

It will be observed that the vertically adjustable bed of the invention may be dismantled and repaired on site and comprises a relatively simple structure which does not require a specialized maintenance man. Still further, the force applying element 154 provides means whereby the springs 146 may be pre-loaded and thus be effective through the entire range of vertical adjustment of the head assembly 64, i.e. by pre-loading the springs they will still be under compression when the head assembly is adjusted to its maximum vertical limit.

This expedient is not provided in conventional vertical adjustable beds and thus when an operator gets to the upper portion of the vertical adjustment of conventional beds, the springs are no longer effectively aiding in the vertical adjustment of such beds and excessive manual effort is required. Still further, the operating handle is located at the upper end portion of the end assemblies and thus relatively little stooping, if any, is required by an operator of the bed so that a maximum amount of force can be concentrated at the operating handle assembly 26.

It will be obvious to those skilled in the art that various changes may be made without departing from the spirit of the invention and therefore the invention is not intended to be limited to what is shown in the drawings and described in the specification but only as indicated in the appended claims.

What is claimed is:

1. An end assembly for use in a vertically adjustable bed comprising vertical support means for engaging a support surface, a head assembly reciprocally supported on said support means for vertical adjustment thereon, force transmitting means on said head assembly and including a portion movable therewith for progressively adjusting said head assembly with respect to said support means, and counterbalance means interposed between said support means and head assembly and normally applying force through and beyond the entire range of vertical adjustment of said head assembly with respect to said support means, said support means comprising a pair of spaced parallel vertical support legs, said head assembly comprising a pair of tubular spaced parallel vertical sleeves respectively telescoped and guidingly engaged on said vertical legs, a horizontal head element extending

between upper end portions of said sleeves, said sleeves including opposed, vertically extending slots determining the range of vertical adjustment of said head assembly, a head member disposed substantially parallel to said vertical legs and fixedly secured at opposite ends to said vertical support legs, said head member including a central reaction portion including an internally threaded, vertical bore portion, a support member disposed parallel to said head element and fixedly secured at opposite ends to said vertical sleeves, said force transmitting means comprising a vertically extending shaft depending from said head element and including an externally threaded portion engaged in said threaded bore to react against said reaction portion and head member during rotation, said support member including transmission means mounted thereon and operatively connected to said shaft whereby rotation of said shaft causes simultaneous vertical movement of said head element, support member, vertically extending shaft and vertical sleeves in guided relation on said support legs due to reaction forces centrally of said head member and equally distributed on said support legs.

2. The structure of claim 1 wherein said counterbalance means comprises coil springs disposed in abutting relation between said support legs and said head member.

3. The structure of claim 2 including pressure applying means adjustably retained on said head member and engaged with one end of said coil springs for matching the residual force imposed by said coil springs.

4. The structure of claim 1 wherein the threaded portion of said shaft and said threaded bore comprise a thread having a relatively shallow pitch to prevent "back driving" of said head member with respect to said support means due to the counter balancing means.

5. The structure of claim 1 wherein said force transmitting means comprises a manually rotatable handle operatively connected to said vertically extending shaft.
